Patented Mar. 29, 1927.

1,622,687

UNITED STATES PATENT OFFICE.

OTTO E. SZEKELY, OF MOLINE, ILLINOIS.

INTERNAL-COMBUSTION ENGINE.

Application Filed November 12, 1925. Serial No. 68,702.

My invention has reference to internal combustion engines, and aims to provide a novel arrangement whereby the same motor may be adapted for use in either a vertical or horizontal position, the only substantial difference being in the style of the base which is employed for the support of the motor. The manufacturer of the motor is thereby enabled to comply with the wishes of the purchaser in this respect, without any marked difference in the cost of production, such as would be required in the building of two distinct motors, one of the vertical, and the other of the horizontal type. There is also a considerable saving in the matter of drawings, patterns, etc., of which only one set is required, and without the danger of confusion of parts and the bother accompanying the use of two complete sets.

The construction, arrangement, and operation of the various parts of the invention will more fully appear from the following specification, taken in connection with the accompanying drawings, in which:

Fig. 1 shows the invention with the motor disposed in a horizontal position.

Fig. 2 shows the same in a vertical position.

Referring first to Fig. 1, the reference number 1 indicates a base, of oblong form, upon which is mounted in horizontal position a crank-shaft casing 2, provided with a cylinder extension 3, to which is attached a head 4. In the base 1 is an oil-supply tank 5, connected by a pipe 6 with the carburetor 7 of the engine. The working parts of the engine are not involved in the present application, except in so far as they conform to the position of the motor in its alternative positions. In the lower face of the casing 2 is an opening 8, normally closed by a plate 9, having a depressed portion forming an oil-pan 10 beneath the casing. Said plate 9 is removably held in place by means of bolts 11, entering openings in the casing.

The end of the casing 2 opposite to the head 4 is also provided with an opening 12, closed by a plate 13, by means of bolts 13^a passing through said plate and into the end of the casing. The plate 13 is of suitable dimensions to be used interchangeably as a closure for either the opening 12 or the opening 8, the bolts 13^a being spaced similarly to the bolts 11, so as to enter the openings therefor.

In Fig. 2 the motor is shown supported in an upright position, the carburetor 7 being connected by a pipe 14 with a supply tank 15, supported on a bracket 16, projected outwardly from a plate 17, secured to the motor by bolts 18, so as to form a closure for the opening 8. As an alternative arrangement the supply tank can be supported apart from the motor, and the opening 8 closed by the plate 13, in the manner above mentioned. The motor is supported in this position on a base 19, provided in its upper part with an oil pan 20, and secured to the motor by means of bolts 21, held in the openings formerly occupied by the bolts 13. In fact, one set of bolts may be used in both cases, if desired.

It sometimes occurs that after a motor has been used for a time it is found desirable to operate the same in a different place, with differences as to space, etc. If the space is more limited than formerly the motor can be made to conform thereto by merely substituting the base 19 for the base 1, and making such changes as to the supply tank 80 as may be necessary to conform thereto. This will eliminate the necessity of procuring an entirely new engine, or exchanging the old engine for a new one.

In Fig. 1 an additional fastening means is shown at 21, and such bolt can be employed in the other arrangement for holding one end of a retaining strap 22 for the tank 15.

What I claim as my invention, and desire to secure by Letters Patent, is:

1. In an internal combustion engine, a crank-shaft casing, and fixed base therefor, provided in its upper part with a lubricant container, and adapted to hold said casing in a horizontal position, one of the ends of said casing being fitted for mounting in a vertical position.

2. In an internal combustion engine, a crank-shaft casing fitted on one of its sides for mounting on a base in a horizontal position, and having an opening in said side, and similarly fitted at one of its ends for support in a vertical position, with an opening in said end, and a plate adapted for alternative attachment to said casing, to form a closure for either of said openings.

3. In a device of the class described, a motor, including a crank-shaft casing fitted for support on one of its sides or one of its ends, and provided with an opening in each thereof, a base adapted to hold said casing in a horizontal position, and fuel

supply tank contained in said base, a closure plate for the opening in the end of said casing, and a closure plate for the opening in the side of said casing, fitted with a bracket adapted for the support of a fuel supply tank when said casing is mounted in a vertical position.

4. In a device of the class described, a motor, including a crank-shaft casing provided with means for support in either a horizontal or a vertical position, and having openings in its side and end for use in such

alternative positions, a base adapted to hold said casing in a horizontal position, and containing a fuel supply tank, a closure for the opening in the side of said casing, provided with an oil-pan, and a plate forming a closure for the opening in the end of said casing, and adapted to be used interchangeably as a closure for said first-named opening.

In testimony whereof I affix my signature.

OTTO E. SZEKELY.
